UNITED STATES PATENT OFFICE.

FRANK L. HANER, OF SAN DIEGO, CALIFORNIA.

AMUSEMENT OR GAME APPARATUS.

Application filed July 3, 1923. Serial No. 649,266.

To all whom it may concern:

Be it known that FRANK L. HANER, a citizen of the United States of America, residing at San Diego, in the county of San Diego and State of California, has invented new and useful Improvements in Amusement or Game Apparatus, of which the following is a specification.

The present invention has for its purpose to provide, in an amusement device or game apparatus, a construction including a plurality of inflatable bodies and a plurality of toy automobiles, or other vehicles or the like mounted upon tracks and means for actuating said automobiles or the like whereby, when the bodies are properly inflated, the automobiles will properly ascend the tracks and operate a signal proclaiming the successful player as the winner.

Another purpose is to provide a device of this character particularly adapted for use at places of amusement where a number of persons may play the game, prizes being awarded to the winners.

Still another purpose is to provide an apparatus so constructed that either air, gas or liquid can be used for inflating the bodies and actuating fan wheels for operating the automobiles, the inflatable bodies being of such a character that should they be over-inflated they will burst, and obviously should there be a number of persons playing, the consecutive popping of the bodies will add zest to the fun and excitement of playing the game.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a view in side elevation of the improved amusement or game apparatus constructed in accordance with the invention.

Figure 2 is a plan view.

Figure 3 is a view in front elevation.

Figure 4 is an enlarged detail view of the fan wheel and its drum.

Figure 5 is a detail view of the means to

be actuated by a toy automobile for lighting an electric bulb.

Referring to the drawings, 1 designates the frame as a whole which comprises the forward and rear upright portions 2 and 3. The latter portion has an upper inclined platform 4 upon which a plurality of tracks 5 are in pairs, there being a toy automobile or other vehicle or the like 6 operable on each pair. A shaft 7 is journaled in suitable bearings on the rear upper portion of the rear upright part of the frame and mounted for individual rotation on the shaft are pulleys 8.

In bearings on the lower portion of the rear upright part of the frame is a shaft 9 and individually revoluble thereon are drums 10 rotatable with which are fan wheels 11. Attached to and adapted to wind on each drum is a cord or cable 12. These cords or cables pass around the individual rotatable pulleys 8 and are, in turn, connected to the plurality of toy automobiles. Obviously, as each drum rotates, its cable or cord will wind thereon and cause the vehicle or automobile attached to the cable or cord to ascend its track.

Rising from the upper part of the platform 5 and disposed between the rails of each pair of tracks is a standard, post or the like 13 carrying an electric bulb 14, there being a suitable push button or the like 15 at the base of the post in a position to be engaged by the automobile or other vehicle when it reaches the highest point on the track. The push button is electrically connected in a conventional manner (not shown) with the bulb and, when actuated, the bulb is lighted which will indicate the winner to those who are playing the game. It is possible for more than one to be successful and in this case the first winner may be awarded the best prize. Obviously, the first and second winners may be awarded the first and second prizes.

The forward upright part of the frame supports a plurality of pipes 16 connected to an air, gas or liquid reservoir or container 17, by means of a pipe 25, for supplying such fluid thereto. The fluid in the container or reservoir may be under pressure so that it will pass through the pipe with sufficient force to inflate inflatable bodies or balloons 18. Each pipe 16 is constructed of the upright and horizontal sections 19, 20

and 21 connected by the usual elbows as shown. The upright portions are, in turn, connected with the lower horizontal pipe 22 which terminates in a spray nozzle 23.

5 Each spray nozzle is located in a position so that the column, spray or stream of fluid, whether air, gas or liquid, may impinge with the blades of the fan wheel. In other words, the nozzles are disposed so that the fan wheels will act as overshot revoluble members. It is obvious that a nozzle may be adjacent each fan wheel and, since the fan wheels and drums are individually revoluble, the cables or cords 12 will individually actuate and, in turn, individually cause their toy automobiles or other vehicles or the like to individually ascend their tracks.

20 The pipe 25 connects to a valve 26 which, in turn, connects to a short pipe 27. A horizontal pipe 28 extending adjacent the front of the forward upright part 2 of the frame is connected to the short pipe 27 by means of a T 29. The vertical pipes 19 rise from 25 the horizontal pipe 28, as shown in the front elevation in Figure 3. A long valve stem 30 provided with a handle 31 is provided for the purpose of opening and closing the valve 26 which, when opened, permits air, 30 gas or liquid under pressure to enter the plurality of pipes 19.

35 A player's control valve 32 is carried by each of the horizontal sections 21 of the pipe 16 so that each player may control the passage of air, gas or liquid to the inflatable body or balloon. In fact, an inflatable body or balloon 18 is carried by a nipple or nozzle 33 which is carried by a union 34 upon each horizontal section 21.

40 The accompanying drawings disclose at least six pipes or conduits 16 although it is obvious that any number of pipes may be used. However, in this case six players arrange themselves in front of the apparatus, 45 their right hands being placed upon the handles of the valves 32 and at a suitable signal given by an attendant the players actuate the handles of the valves 32 sufficiently to open the valves which will permit air, gas or liquid to pass through the pipes 16 and inflate the bodies or balloons 18. In their eagerness to win the game, one or another or several of the players may permit an excessive quantity of fluid to pass through 55 the pipes which will cause the bodies or balloons to burst and in this instance the toy automobiles or vehicles which are operated by the same discharge of fluid will fail to reach the upper portion of the platform 5. 60 It will be noted that an inflatable body 18 is connected with each of the pipes by which an automobile is put in operation. The valves 32 may be skillfully enough manipulated to start the vehicle on its upward movement and simultaneously inflate the 65

connected balloon 18. If the valve is closed quickly enough, the air which will have been trapped in the balloon will leave the latter and pass through the pipe or conduit and continue to operate the fan wheel after the 70 main supply has been cut off and the vehicle having been started on its upward movement by air from the main supply, will be continued to the upper end of the platform by the air which will, after the 75 valve 32 is closed, continue to operate the fan wheel. Thus, the skill in manipulation consists in opening the valve 32 for a sufficient time to inflate the member 18 and carry the vehicle nearly to the conclusion of 80 its full travel, thereby trapping enough air in the balloon to complete the necessary movement of the vehicle.

The invention having been set forth, what is claimed is:

85 1. An amusement or game apparatus including a frame, a reservoir containing fluid under pressure, a plurality of conduits operatively connected to the reservoir and provided with inflatable bodies, means on 90 each conduit for controlling the fluid to the inflatable body, said conduits terminating at one end of the apparatus in a plurality of discharge nozzles, a plurality of movable devices on the tracks of said frame, 95 and means actuated by the fluid discharged from the nozzle and in turn operatively connected to the movable devices for moving them along the tracks as the bodies are inflated, said inflatable bodies discharging 100 their contents through said nozzles after the closing of said controlling means for continuing the operation of said actuating means.

105 2. In an amusement apparatus, a frame, a plurality of movable devices operable upon tracks on the frame, means operable by fluid pressure and operatively connected to said devices for moving them on their tracks, signals assigned to and operable by each 110 device as it reaches its destination, and a plurality of inflatable members to be ruptured on over-inflation but to continue the operation of said means after the cessation of said fluid pressure.

115 3. In an amusement or game apparatus, a frame, a plurality of racing devices operable upon tracks on the frame, means operated by fluid pressure and operatively connected to said devices for moving them on 120 their tracks, a signal assigned to each device and operable as the latter reaches its destination, and a plurality of inflatable bodies inflatable by the fluid under pressure and rupturable upon over-inflation but supplying the operation of said means after the 125 cessation of said fluid pressure.

In testimony whereof he affixes his signature.

FRANK L. HANER.
